ROAD SIGNAL

Elmer W. McDonald, Tustin, Mich.

Application September 20, 1937, Serial No. 164,647

1 Claim. (Cl. 88—78)

This invention relates to signals, and particularly to a safety device which is adapted to signal when another vehicle is approaching from the opposite side of a hill.

5 One of the prime objects of the invention is to design a very simple, practical and compact signal device which can be located on the side of a road, upon the top of a hill and provide reflecting means so arranged that the light rays 10 from an oncoming vehicle will be reflected up and outwardly and downwardly in the direction of travel of the vehicle, so that they reach the eyes of a driver or pedestrian approaching from the opposite side of the hill.

15 The loss of lives and property due to motorists colliding at the point above mentioned is very large, and the present invention is designed to eliminate such accidents.

20 Another object of the invention is to design very simple and economical means for the purpose described, and particularly adapted for night driving, which will warn motorists of each other's approach though hidden from each other by a hill or other natural obstructions.

25 With the above and other objects in view, the present invention consists in the combination and arrangement of parts, hereinafter more fully described, illustrated in the accompanying drawing, and more particularly pointed out in the appended claim, it being understood that changes 30 may be made in the proportion, form, size, and minor details of construction without departing from the spirit or sacrificing any of the advantages of the invention.

35 In the drawing:

Fig. 1 is a schematic view of a portion of a hill with my reflector signal located on the hill and a vehicle approaching on the one side.

Fig. 2 is an enlarged side elevational view of 40 the tower in which the reflectors are mounted, parts being broken away to show the interior.

Fig. 3 is a rear view thereof.

Fig. 4 is a fragmentary view showing a different type reflector.

45 Fig. 5 is a fragmentary view showing a visor over the window opening.

Referring now more particularly to the drawing in which I have shown the preferred embodiment of my invention, the numeral 7 indicates a tower which can be formed of any desired material, the frame being preferably made up of structural material, suitably covered to form a reasonably dark interior, the base 8, being anchored in position by means of anchor bolts 50 9 or other securing means.

The tower 7 can be of any desired height to suit the needs of the particular location, and is provided with an opening 10 in the front wall thereof, and this opening is adapted to be covered by a sheet of plain glass 11 or other transparent material to exclude dust, dirt, and moisture. Angularly disposed ways 12 are provided in the lower end of the tower, and a mirror reflector 13 is mounted therein so that light rays from the headlights of an oncoming vehicle B will strike 10 the angularly disposed mirror reflector 13 and be projected upwardly as indicated by the arrows, the back wall section 14 in the back of the tower being removable to facilitate cleaning, removal, or adjusting of the mirror.

15 The reflected light rays from this reflector 13 are reflected upwardly as indicated by the numerous arrows, and strike a similarly mounted reflector 15, and these light rays are then reflected downwardly through the window 16 provided in the rear wall of the tower, a preferably red transparent glass or panel 17 being provided in said window so that the light will be red and serve as a warning or danger signal to an approaching 20 motorist on the opposite side of the hill.

25 In Fig. 4 of the drawing I have shown a slightly different construction, a glass bulb or globe 18 being provided in the upper end of the tower, this globe being supported or hung in any desired manner, however, I prefer to use a depending bracket 19, having bulb encircling webs 20 which secure it in position so that the light rays will be reflected through the window in the tower.

30 In Fig. 5 of the drawing I have shown a visor 22 over the window to shield the window from the sun's rays and from rain and/or snow.

35 From the foregoing description it will be obvious that I have perfected a very simple, practical and economical reflector signal for warning motorists of cars approaching from opposite 40 directions.

What I claim is:

A signal device of the character described and comprising a closed, rigid, light-proof tower permanently anchored on the top of a hill and on 45 the side of a highway passing over said hill, said tower being within the light range of the headlights of a motor vehicle traveling up said hill on said highway, angularly disposed guides mounted on the side walls of the tower at a 50 point spaced from the lower end thereof, an angularly disposed reflector mounted in said guides and extending entirely across the tower, a door in the tower to permit removal of the reflector, guides in the upper end of the tower, 55

- an angularly disposed reflector mounted therein; a window in the back wall of the tower in alignment with said upper reflector, a visor mounted over and forming a shield for said window, a 5 transparent panel mounted in the front wall of the tower in alignment with the lower reflector, said lower reflector being arranged so that the light rays from an upwardly approaching vehicle

on said highway are intercepted by the lower reflector and reflected upwardly to the upper reflector, which upper reflector is arranged to reflect said light rays downwardly through the window in the back wall of the tower so that they reach the eyes of an operator approaching from the opposite side of the hill. 5
